A. Randolph Jr., attorney

UNITED STATES PATENT OFFICE.

LEWIS PITTS, OF DAHINDA, ILLINOIS.

GRADE-CROSSING.

1,325,169.

Specification of Letters Patent. Patented Dec. 16, 1919.

Application filed March 26, 1919. Serial No. 285,209.

To all whom it may concern:

Be it known that I, LEWIS PITTS, a citizen of the United States, residing at Dahinda, in the county of Knox and State of Illinois, have invented certain new and useful Improvements in Grade-Crossings; and I do hereby declare the following to be a full, clear, and exact description of the invention, such as will enable others skilled in the art 10 to which it appertains to make and use the same.

My invention relates to improvements in railway grade crossings, and more particularly to a grade crossing of the portable 15 type.

An important object of this invention is to provide a railway grade crossing constructed of a plurality of sections adapted to be readily placed in position or removed 20 without interfering with the rail section.

A further object of the invention is to provide a railway grade crossing having novel means of preventing dirt, ice, and so forth from accumulating between the rail 25 sections, and the crossing, whereby the free passage of rolling stock is assured.

A further object of the invention is to provide a grade crossing of the character described, which is efficient, of highly simplified construction, and durable in wear.

Other objects and advantages of the invention will be apparent during the course of the following description.

In the accompanying drawings wherein 35 for the purpose of illustration is shown the preferred embodiment of my invention,

Figure 1 is a transverse section through a railway track, showing my improved grade crossing in elevation,

Fig. 2 is a similar view, showing my improved grade crossing in section, and

Fig. 3 is a fragmentary perspective of one of the inclines embodied in the invention.

In the drawings, wherein for the purpose 45 of illustration is shown, the preferred embodiment of my invention, the numeral 5 designates a railway tie having a pair of rails 6 secured thereto. Spikes 6' engage the bases of the several rails and secure the same 50 to the tie.

Approach is had to the crossing through the medium of inclines generally designated by the numeral 7. The inclines 7 are disposed on the outer side of the rails 6 and 55 are preferably formed of metal castings hav-

ing supporting uprights 8 formed integrally with longitudinally extending inclined tread surfaces 9. The uprights are provided with outwardly extending tie contact members 10. The inner longitudinal edges of the inclines 9 are provided with vertically disposed uprights 10' snugly engaging the balls of the several rails. L-shaped flanges 11 are formed integral with the uprights 10' and engage the bases and webs of the rails as 60 clearly illustrated in Fig. 2 and prevent the access of water to beneath the inclines 7. The outer sides of the vertical members 8 are provided with horizontal shoulders 12 which extend over and engage the spikes 6'. 65 As clearly illustrated in Fig. 3, the ends of the inclines 7 are provided with apertured shoulders 12' for receiving spikes 13'.

A pair of relatively large casings or sections 13 and 14 are disposed between the 70 rails inwardly of the inclines 7 and are secured to the ties by spikes 15. The spikes 15 extend through apertured shoulders 15' in the end portions of the several sections. The sections 13 and 14 are provided along 75 their outer longitudinal edges with vertical members or uprights 18. The uprights 18 are formed integral with longitudinally extending flanges 19 which are L-shaped in cross section. The flanges 19, as clearly 80 illustrated in Figs. 1 and 2, snugly engage the bases and webs of the inner sides of the rails. Horizontally disposed shoulders 19' are formed integral with the uprights 18 and extend over the spikes 6'. The sections 85 13 and 14 are provided with a plurality of longitudinally extending parallel supporting uprights 16 disposed inwardly of the uprights 18.

The section 14 is provided in its inner 90 longitudinal edge with a groove 21 adapted for receiving a tongue 22 carried by the section 13. The tongue 22 is of considerably less width than the groove 21 thereby permitting lateral movement of the several sections with relation to each other. A flange 23 extends over the top of the section 14 and thereby prevents the entrance of all foreign elements into the groove. As clearly illustrated in Figs. 1 and 2, the sections 13 and 100 14 are provided on their outer faces with grooves 25 adapted to afford draft animals a reliable grip on the crossing.

In installing my improved grade crossing, it will be apparent that the several in- 105 110

clines are positioned as illustrated in the drawings as rigidly secured to the ties by the spikes. The several sections are now positioned between the rails and rigidly secured to the ties by the spikes.

While I have shown and described the preferred embodiment of my invention, it is understood that I may make such minor changes in arrangement and construction of parts, as will remain within the spirit of the invention and scope of the appended claims.

Having thus described my invention, what I claim is:—

1. A grade crossing comprising a pair of inclines arranged on the outer sides of a pair of rails, and having the inner longitudinal edges thereof in contact with the balls of said rails, a pair of interlocking tread sections disposed between said rails and adapted for relative lateral movement, and longitudinally extending flanges carried by said inclines and said tread sections and terminating directly beneath the balls of the rails, said tread sections having longitudi-

nally extending grooves in the upper sides 25 thereof.

2. A grade crossing comprising a pair of inclines arranged on the outer side of a pair of rails, a pair of tread sections arranged between said rails, means to secure 30 said inclines and said tread sections in position, longitudinally extending flanges carried by said inclines and said tread sections and having engagement with said rails, a longitudinally extending guide-way carried 35 by one of said tread sections, and a longitudinally extending tongue carried by the other of said tread sections and arranged in said guide-way, said longitudinally extending flange being of a lesser width than said 40 guide-way, whereby lateral movement of the several sections is permitted.

In testimony whereof I affix my signature in presence of two witnesses:

LEWIS PITTS.

Witnesses.

CLARENCE D. PETERS,
C. R. SHERMAN.
